US0D1101719S

(12) **United States Design Patent** (10) **Patent No.:** **US D1,101,719 S**
(45) **Date of Patent:** **** Nov. 11, 2025**

(54) **AIR PURIFIER HEADPHONES**

(71) Applicant: **Dyson Technology Limited**,
Malmesbury (GB)

(72) Inventors: **Mark Joseph Staniforth**, Bristol (GB);
Hannah Jayne Jobling Hersey,
Newcastle (GB); **Simon Brian McNamee**, Bristol (GB); **Howard Shi-How Cheng**, Swindon (GB); **Ben Lawson**, Durham (GB)

(73) Assignee: **Dyson Technology Limited**,
Malmesbury (GB)

(**) Term: **15 Years**

(21) Appl. No.: **29/993,221**

(22) Filed: **Mar. 13, 2025**

Related U.S. Application Data

(63) Continuation of application No. 29/941,443, filed on May 9, 2024, now Pat. No. Des. 1,070,808, which is a continuation of application No. 29/839,499, filed on May 20, 2022, now Pat. No. Des. 1,042,396.
